KNITTING MACHINE

Kenneth Howie, Norristown, Pa., assignor to
 Wildman Mfg. Co., Norristown, Pa., a corporation of Pennsylvania

Application July 26, 1946, Serial No. 686,422

10 Claims. (Cl. 66—110)

1

This invention relates to knitting machines, and is especially applicable to full fashioned knitting machines of the Cotton type, although not limited thereto.

A general object of the invention resides in the provision of an improved construction and arrangement of the stitch forming elements of such machines.

A further general object resides in the elimination or reduction of the frequent breakage of jack sinker noses prevalent in current machines of this type.

Other and further objects and advantages of the invention will appear from the following detailed description of preferred embodiments of the same.

The invention comprises the combinations and arrangements of parts hereinafter described and claimed.

In the accompanying drawings of illustrative embodiments of the invention

Fig. 1 is a partially diagrammatic side view illustrating an arrangement of jack sinkers, dividing sinkers, sinker and divider bars, needles, and yarn carriers according to the invention, in the relation of the parts during laying of the yarn.

Fig. 2 is a similar view showing the relation of the parts after advance of the jack sinkers.

Fig. 3 is a similar view showing their relation after advance of the dividing sinkers.

Fig. 4 is a similar view showing the relation existing as the new course is being drawn into the fabric and the old course is being pressed off the needles.

Fig. 5 is a diagrammatic view illustrating one mode of operating the sinker and divider bars.

Figs. 6 and 7 are partially diagrammatic side views of a modified arrangement of sinkers, dividers, and control bars, in their notch aligning and nose aligning positions, respectively.

Full fashioned knitting machines of the Cotton type, as shown, for example, in my prior Patents 1,958,823 and 2,248,501, issued May 15, 1934, and July 8, 1941, respectively, employ jack sinkers and dividing sinkers to sink the yarn between the needles. For brevity these may be termed "sinkers" and "dividers" respectively.

The sinkers are advanced sequentially, usually between alternate pairs of needles, by the operation of the slur cock as the yarn is fed to them. They come to rest against the verge-plate or folding bar, and some means, as the sinker hook means of Patent No. 1,958,823, is provided to hold them in this yarn measuring position.

2

After the new yarn has been measured by the individually advanced sinkers, the dividers are advanced en masse in the intervening needle spaces, the needles dropping back relative to the sinkers during this operation. The yarn measured by the sinkers is thus evenly divided into sinker loops projecting between each pair of active needles.

Thereafter, by downward movement of the needle bar, the needle hooks are caused to embrace the new yarn, and the needles are then pressed and draw the needle loops of the newly laid course of yarn through the course previously on the needles. The old course being supported on the knockover bits is pressed off the needles 15 on the knockover bits as they descend, leaving the fabric secured on the needles by the newly formed course of needle loops.

In the conventional machine, except as the 20 dividers are modified by selvage slots, all the sinkers and dividers have uniform long noses, and as the needles go down to draw the stitches over the knockover bits, the entire group of sinkers (i. e., jack sinkers and dividers) is retracted 25 as a unit by the common catch bar. Thus relative motion occurs between the needles and all the sinkers, allowing the sinker loops to be drawn off the noses of the sinkers and down into the fabric.

30 After this operation, relative motion again occurs between the needles and the noses of the sinkers, bringing the newly formed course of fabric into the space between the sinker noses and the knockover bits so that the newly formed 35 course is held down by the sinker noses and stripped down onto the stems of the needles during raising of the needle bar to prepare for the ensuing operation.

In the conventional fine gauge machines of 40 this type, very little breakage of dividers occurs, but breakage of the noses of the jack sinkers is experienced with considerable frequency. Such breakage nearly always occurs at the root of the jack sinker nose, the break extending from 45 the yarn notch to the lower edge of the nose in a rather uniform arc. The explanation which appears to account for this breakage is believed to be as follows:

Machines of this type run at considerable 50 speeds—80 courses per minute, for example. Thus, in fine gauge machines especially, the jack sinkers must be advanced by the slur cock very rapidly, so that each will draw off its full quota of yarn from the yarn carrier before the intervening yarn is snubbed by the operation of the

next advanced jack sinker. Otherwise yarn breakage would occur. This factor necessitates that the jack sinkers be shot home to their forward position against the folding bar or verge plate, and be suddenly stopped thereat, all very quickly. As above noted, the jack sinkers and dividing sinkers in conventional machines are operated by a common catch bar and are provided with noses of uniform length, this length being quite extended to enable accommodation of the several yarn carriers between the sinker notches and the needles while keeping the ends of the sinker noses in fabric hold-down position. The shooting home of the jack sinkers in itself causes the long sinker noses thereof to be set into vibration.

In addition, during the laying of the stitches, the yarn carrier ends of the threads are loose, but the previously laid ends are held against movement. Thus, as a jack sinker draws yarn from the yarn carriers and sinks it between the needles, the yarn reeves through the jack sinker notch, and this reeving action also produces vibration of the sinker.

As the main body of the sinker behind its notch is restrained against free vibration by the sinker mounting head and by the yarn itself, the vibration thus produced tends to concentrate in the unrestrained nose portions of the sinker. The continued vibration of the nose portion of the sinkers thus produced ultimately results in fatigue of the metal at the root of the sinker noses and leads to the breakage frequently experienced thereat.

In the present invention the frequent breakage of the jack sinker noses is avoided by a special construction of these sinkers, and the operation of the sinkers in relation to the associated parts of the machine is modified in an advantageous manner, which, among other things, enables a successful operation employing very short nosed sinkers with long nosed dividers.

In the embodiment of the invention illustrated in Figs. 1-4, the dividing sinkers 10 are of conventional form with the usual long nose portions 10c (measured from the sinker notches 10b), but the jack sinkers 11, which in the conventional form are subject to breakage as aforesaid, are provided with very short noses 11d (measured from the notch 11b) which avoids breakage of the noses.

In conventional practice, it is customary to provide a single compound-motion catch bar to retract the jack sinkers and divider sinkers as a unit, and to arrange for raising of the catch-bar to free the jack sinkers therefrom for advancement by the slur cock. In contradistinction to this arrangement, in the present invention an improved retracting means is provided comprising a divider bar and a sinker bar independently movable in coordinated relation to each other. Thus, in the illustrated arrangement of Figs. 1-4 the dividers 10 are controlled by a divider bar 12 having rear and front walls 12a and 12b of equal height, which can simply be advanced and retracted to move the dividing sinkers, and the jack sinkers 11 are controlled by a separate sinker bar 13, which does not rise to allow the sinkers to pass under it, but is itself advanced ahead of the sinkers prior to the operation of the slur cock. The sinker bar 13, in the form shown, comprises a single hook-shaped member 13a carried by a slide member 13b, and is adapted to retract the sinkers 11 into contact with an appropriately placed abutment. In the form of Figs. 1-4 the

abutment is provided by the front portion 12c of the divider bar 12, and is contacted by the backs of the sinker-butts or tabs 11c of sinkers 11.

With this arrangement, when the sinkers and dividers are retracted to the position of Fig. 1 prior to the laying of the yarn, the long noses 10c of dividers 10 project between the needles 14 while the short noses 11d of the jack sinkers 11 are entirely retracted from the needle spaces. Thus the divider noses are kept in place over the work 15, and yet ample space is provided to accommodate the several yarn carriers, of which one is shown at 16.

When a course of yarn is about to be laid, the sinker bar 13 is advanced from the position indicated in Fig. 1 to its forward position illustrated in Fig. 2, the jack sinkers 11 remaining, however, in the position of Fig. 1, ready to be advanced sequentially and rapidly to the position of Fig. 2 by the action of the slur cock. The sinkers 11, as they reach the position of Fig. 2 and strike the verge plate or folding bar (not shown) may be retained thereagainst by any suitable means; for example, by sinker hooks, as shown in my Patent No. 1,958,823, issued May 15, 1934.

On completion of the slurring operation, the divider bar 12 is advanced from the position of Fig. 2 to that of Fig. 3. In this position the yarn notches 10b of the dividers are brought into alignment with the yarn notches 11b of the sinkers, and the needles 14 dropping back as usual, the stitches are divided equally between the needles. At this point, in this illustrative embodiment the abutment 12c carried by the divider bar may contact the backs of the jack sinkers, as shown, and this contact may be maintained during release of the sinker hooks, above mentioned.

At the stage indicated in Fig. 3, the needles 14 are descending, and after their beards have embraced the newly laid course of yarn, are pressed in the usual fashion.

During the movement to the "press" position 45 the notch alignment is maintained. In the arrangement of Figs. 1-4 the gripping of the sinker tabs 11c between the sinker and divider bars 12 and 13 maintains it.

The alignment of the sinker and divider notches is also maintained during the pressing and during the first part of the draw-down operation until the loops are fully assembled in the heads of the needles and extend substantially vertically between them and the sinker and divider notches. Thereafter the needles continue to descend and the sinkers and dividers are retracted relative to them as the sinker loops are drawn down along the sinker and divider noses to the point at which they are drawn off the tips 60 of the noses and down into the old fabric, which is being supported on the knockover bits as shown in my prior patents above noted.

In the practice of the present invention, when the assemblage of the stitches in the heads of the needles is completed the dividers begin to retract more rapidly than the sinkers. This removes the divider bar 12 from contact with the backs of the sinkers 11, but this causes no difficulty with flying sinkers during the draw-down and delivery of the loops, as the loops are not pulled tight on the noses of the sinkers and dividers.

In producing the relative motion between the sinkers, dividers and needles during the draw-down operation, the short nosed sinkers 11 may

be held practically stationary and the relative motion may be produced by dropping out of the needles relative to the sinkers and by retraction of the dividers to align their noses with those of the sinkers at the moment when the loops drop off the noses. This dropping away of the needles during the draw-down operation also reduces the speed of retraction of the divider bar 12.

At the moment when the sinker loops fall off the ends of the sinkers and dividers, the ends of the sinker and divider noses are aligned, as shown in Fig. 4, and the stitches are thus delivered to the fabric simultaneously. The new loops are then drawn into the fabric, and as the needles go to their lowest position the old loops are knocked over the heads of the needles by the knockover bits, as is well known. Following the knockover operation, the motion of the sinker and divider bars is reversed, and the sinkers and dividers are advanced to hold down the fabric during rising of the needles. Preferably the sinkers and dividers are advanced so that the needles which are rising a short distance from the press position pass upwardly between the sinkers and dividers in substantial alignment with the yarn notches thereof. Thus the noses of the sinkers and dividers overlie the fabric and strip down the new loops onto the stems of the needles.

When the needles have passed through the throats of the sinkers and dividers they continue to rise to the top of their stroke, and then lower slightly to remove the fabric from the underside of the sinkers and dividers and lay it upon the knockover bits. During this last rising and lowering action, the sinkers and dividers may be retracted to their starting position illustrated in Fig. 1.

Special provision may be made for retraction of the sinkers and dividers beyond the point indicated in Fig. 1, as during fashioning, for example. In this operation, during the narrowing the sinkers and dividers are retracted a little further than in straight knitting to clear the narrowing points when they move across the needles.

The sinker and divider bars may be given their fore and aft motions respectively by any suitable means, as by linkages similar to those employed for giving fore and aft motion to the ordinary catch bar, which may be driven by cams suitably designed to impart the desired movements to the bars in timed relation to the operation of the machine as a whole. One form of such means is illustrated in Fig. 5. As there shown, the divider bar 12 is engaged by a link 20 pivoted to one end of a bell crank lever 21, which turns about an axis 22 and has at its other end a roller 23 bearing against the periphery of the divider bar operating cam 24, which may be mounted on the main shaft of the machine and has its periphery designed to impart to the dividers 10, in timed relation to the operation of the machine as a whole, the movements above indicated. The sinker bar 13 in this arrangement is connected by a pivoted link 30 to one end of a bell crank lever 31 pivoted on an axis 32, which carries at its other end a roller 33 similarly engaging the surface of a driving cam 34 which may be carried on the same shaft 35 on which cam 24 is mounted. Since the particular shapes of the cams 24 and 34 are determined by the particular cycle of the machine and the proportions and arrangement of the linkages connecting the cam rollers 23 and 33 with the divider and sinker bars

12 and 13, and are matters of design, portions only of cams 24 and 34 are shown for simplicity of illustration.

The forms of sinker and divider bars 12 and 13 shown in Fig. 5 are substantially the same as those shown in Figs. 1 to 4, and in these arrangements the lengths of the sinkers 14, measured from their tabs 14c to their yarn notches 14b, are less than the lengths of the dividers 10 measured from their tabs 10d to their yarn notches 10b.

In the modifications shown in Figs. 6 and 7, provision is made for the use of sinkers and dividers having equal lengths measured from their tabs to their yarn notches. In this arrangement, the sinker tab 40 is relatively short as compared with the divider tab 41, and the divider bar 42 has its forward wall 42b terminated at a height which insures retaining of the divider tabs 41 between the front and rear walls 42b and 42a, but which allows the shorter sinker tabs to move under the wall 42b from the position shown in Fig. 6 to that shown in Fig. 7. In this arrangement the sinker bar 43 has its sinker engaging hook 43a terminating in a rearwardly extending flange 43b which abuts the sinker tabs 40 and follows them under the divider bar wall 42b to align them with the sinker tabs 41 in abutting relation to the rear wall 42a of the divider bar.

The mode of operation of this embodiment of the invention may be generally the same as that of the embodiment shown in Figs. 1 through 5, and in this arrangement the wall 42a constitutes the abutment corresponding to 12c in Fig. 1.

While it is preferred to provide sinker and divider noses of proportionate curvature (eliminating from consideration the selvage slots in the dividers) and to retract them from their stitch measuring positions at rates corresponding to their nose lengths to provide for smooth sliding of the loops toward their release point, such proportional retraction of the sinkers and dividers is not essential in the broader aspects of the invention so long as yarn notch alignment is maintained during measurement of the stitches and nose alignment is attained at the instant the stitches are drawn off the noses and into the fabric.

From the foregoing it will be apparent that the embodiments shown and described are but illustrative and not restrictive of the invention herein disclosed and claimed, and that inventive features and combinations of this disclosure may be embodied in other specific forms.

What I claim is:

1. A full fashioned knitting machine having a group of short nosed sinkers and a group of long nosed dividers, and means for positioning said sinkers and dividers to align their yarn notches for measurement of a course of stitches, and for thereafter altering their relative positions to align their nose tips for simultaneous release of the sinker loops of said course to the fabric.

2. A knitting machine employing sinkers and dividers for measuring the stitches, particularly characterized in that the sinkers have short noses and the dividers have long noses, measured from their respective yarn notches, and in that said sinkers and dividers are retracted from their stitch measuring position at different rates to provide for uniform release of the sinker loops during the draw-down operation.

3. In a knitting machine of the type employ-

ing sinkers and dividers for measuring the stitches, in combination, short nosed sinkers and long nosed dividers, said sinkers and dividers in their advanced position having their yarn notches in alignment, a bar for retracting said sinkers as a group, a bar for retracting said dividers as a group, the said bars being independently retracted during draw-down of the sinker loops to provide for uniform release of the sinker loops to the fabric.

4. A full fashioned knitting machine employing a group of sequentially advanced sinkers and a group of simultaneously advanced dividers, and having retracting means therefor, particularly characterized in that the sinker group retracting means is operable independently of the divider group retracting means.

5. A full fashioned knitting machine comprising a group of sinkers and a group of dividers, and having means for retracting said sinkers from their stitch measuring position and means for separately retracting said dividers from their stitch measuring position.

6. A knitting machine employing sinkers and dividers for measuring the stitches particularly characterized in that the sinkers have a length different from the length of the dividers, and in that the sinkers are provided with retracting means separate from that associated with the dividers.

7. A knitting machine having short nosed sinkers and long nosed dividers adapted, respectively, for sequential and simultaneous advance to stitch measuring position, means for retracting said sinkers as a group during the draw-down operation, means for retracting said dividers as a group during the draw-down operation, said retracting means presenting the tips of said short and long noses in alignment as the new stitches are drawn therefrom, and means for thereafter further reTRACTING said short nosed sinkers.

8. In a knitting machine, a set of dividers, means for retracting the same, a set of sinkers, and a separate retracting means therefor, one of said sets having relatively long noses and the other having relatively short noses measured from their yarn notches to their tips, each set having its yarn notches aligned with those of the other in the stitch measuring position thereof, and said retracting means being arranged to differentially retract said sets and align the nose tips of each set with those of the other for release of the stitches therefrom.

9. In a knitting machine, a set of dividers, means for retracting the same, a set of sinkers, said sinkers being shorter than said dividers, and a separate retracting means positioned forwardly of said divider retracting means, and movable to and fro with relation thereto to permit independent advance and provide for independent retraction of said sinkers, one of said sets having relatively long noses and the other having relatively short noses measured from their tips, each set having its yarn notches aligned with those of the other in the stitch measuring position thereof, and said retracting means being arranged to differentially retract said sets and align the nose tips of each set with those of the other for release of the stitches therefrom.
10. In a knitting machine, a set of short nosed sinkers provided with offset butts, a set of long nosed dividers provided with offset butts, a divider bar engaging the divider butts, a sinker bar lying forwardly of said divider bar and movable toward and from the same, said sinker butts extending into the slot between said divider and sinker bars, and operating means for advancing said sinker bar to a forward position to provide for sequential advance of said sinkers, for advancing said divider bar to effect dividing of the stitches, for separately retracting said sinker and divider bars to align the sinker and divider noses for the knockover operation, and for thereafter further retracting said sinker bar.
